UNITED STATES PATENT OFFICE.

JOHN H. FUNK, OF ST. LOUIS, MISSOURI.

CAR COUPLING.

1,418,784.

Specification of Letters Patent. Patented June 6, 1922.

Application filed March 9, 1921. Serial No. 450,867.

To all whom it may concern:

Be it known that I, JOHN H. FUNK, a citizen of the United States, residing at St. Louis, in the State of Missouri, have invented certain new and useful Improvements in Car Couplings; and I do hereby declare the following to be a full, clear, and exact description of the invention, such as will enable others skilled in the art to which it appertains to make and use the same.

This invention relates to car couplers of the general type shown in the patent to One-sime Hebert, patented December 28th, 1920, No. 1,363,973. In that patent there is disclosed a coupler head pivoted to a draw bar and adapted to interlock with another similar coupler head so that when the said two heads are interlocked the said heads form a rigid mass, whereby press-on train-pipe or other pipe couplings which are mounted on the under side of each head may make a tight joint.

Couplings of the type disclosed in said patent are provided with rigid coupling lugs or hooks projecting forward adapted to interlock with the M. C. B. or Janney type coupler and each coupler head is also provided with a pivoted knuckle operating in a space between the upper and lower sides of each rigid coupling hook, each knuckle being adapted to interlock with a corresponding coupling head of similar type.

The objects of the present invention are:

(1) To increase the rigidity of a pair of interlocked couplers by causing an oblique face on the end of each projecting coupling lug to engage with a curved surface on the end of the draw bar through which the coupling pin passes.

(2) To improve the tripping toe and coupling head of the knuckles in such manner as to make it more difficult to trip said knuckles, and

(3) To improve the releasing lever whereby said knuckles may be tripped to unlock a pair of coupler heads from interlocking engagement with each other.

The invention consists in the combinations and details of construction set forth in the ensuing description, illustrated in the accompanying drawings, and defined in the appended claims.

In the drawings, wherein corresponding reference characters designate corresponding parts throughout the several views:

Figure 1 is a horizontal section through

interlocked coupler heads on a plane above the draw bar;

Figure 2 is a side elevation of the improved coupling;

Figure 3 is a front elevation thereof with a part broken away adjacent to the point of connection of the tripping lever.

In said drawings, 1 designates a hollow coupler head of the type shown in the aforesaid patent; 2 the draw bar pivoted in the coupler head 1 by means of the coupling pin 3. The front end of said draw bar is curved horizontally corresponding to a partly cylindrical surface as indicated at 2^a. 65 On the upper surface of the inner end of the draw bar 2 is a V-shaped protuberance 2^b adapted to engage with a corresponding V-shaped cavity in the coupling head for the purpose of causing said coupling head, when 70 free, to gravitate into alignment with the draw bar. Each coupling head is provided on one side with an opening 1^b, the front edge of which constitutes an abutment 1^a for engaging with the knuckle of a companion coupler in the usual manner. 75

Projecting forward from the front face of the coupling head is a coupling hook or lug 4, having a point 4^a and hook member 4^b designed to interlock with a knuckle of an 80 M. C. B. coupler. The front end of said hook 4 has an inclined face 4^c extending from the point 4^a to the hooks 4^b, and a slot 4^d is provided between the upper and lower sides of said hook 4 within which 85 moves a pivoted knuckle. The disposition and arrangement of the face 4^c of said projecting coupling hook 4 is such, with respect to the curved surface 2^a of the head of the draw bar, that when the front faces of two 90 coupling heads are in contact and the respective hooks 4 are inserted within the openings of the mating couplers, the said surfaces 4^c and 2^a will be in firm contact, and the said hook will substantially touch on said 95 surface 2^a and on the wall of the outer side of the cavity in the head, thus assisting in maintaining rigidity between the two coupling heads when interlocked. 100

The knuckles which are utilized for interlocking two of the coupler heads 1, are designated 5. Each knuckle is pivoted by means of a pin 6 to the coupler head, said pin passing through a projecting portion of the knuckle so that said projecting portion 105 lies in an opening of the coupler head whereby some or all of the draft strain may be

taken from the pin 6. Each knuckle, as stated, is adapted to move horizontally in the said space 4^e of the rigid coupling hook 4. On the outer side of each knuckle is an 5 engaging surface 5^a, inclined as shown, and adapted to engage behind the abutment 1^a of a mating coupler, whereby the said couplers may be interlocked and the inclination of the surface 5^a and its relation to the pivot 10 6 is such that as wear takes place lost motion will be compensated for.

Each knuckle has a transversely projecting portion 5^c constituting a tripping toe. In the present invention this tripping toe 15 has a peculiar formation adapted to interfit with a corresponding formation on the inner side of a hook member formed on the pivoted knuckle. The knuckle head hook, formed so that it may not interfere with the 20 interlocking of said rigid hook with a coupler of foreign type, has its outer surface serving to contact with the tripping toe, so that when pressure is applied to one knuckle to unlock it from its engagement with a 25 mating coupler head, it will, by pressure upon the tripping toe of the other knuckle also unlock said other knuckle. In the said 30 patent to Hebert the curvatures of the tripping toe and of the head of the knuckle where they come in contact, are opposed 35 convex surfaces, whereby when pressure is applied to a knuckle to release it from engagement with a coupler head, the movement is communicated with considerable ease and freedom to the other knuckle. In order 40 to render it more difficult to uncouple, I have formed the contacting portions of the tripping toe and the knuckle head so that they may interfit and tend to hold each other in 45 the locking position, but will yield under sufficient pressure. For this reason there is formed in the toe 5^c a hollow 5^d adapted to interfit with a curved projection 5^e on the head of the corresponding knuckle, and I 50 have also formed a swell 5^f on the toe which engages with a corresponding hollow 5^g on the head. As a result of this construction it will be perceived that the camming action is rendered more difficult because of the relative 55 steepness of the curved surfaces which interfit when the knuckles are interlocked in a pair of mating couplers.

The knuckles are continually pressed outward towards interlocking position by means 55 of a spring 51 seated in a bore in the knuckle and bearing against the sliding pin 50, the outer end of which presses against an abutment 1^c on the coupling head. By this construction it is apparent that even if the 60 spring 51 becomes broken, the several broken pieces will act as one spring since they cannot pass each other.

In order to trip with ease the pair of interlocked knuckles of the construction described, I have provided a long lever 7 ex-

tending perpendicularly and pivoted in the lugs 7^b cast on one outside face of the coupling head, a pin 7^c passing through said lever and lugs. On the upper end of said lever 7 I prefer to mount a wear roller 7^a 70 which comes opposite the opening 1^b and in position to press upon the face 5^b of a knuckle head. When, therefore, the lower end of the lever 7 is moved outward, as by pulling upon the link 7^e or other suitable 75 connection, the roller 7^a presses strongly against the said surface 5^b and releases the knuckle from engagement with the shoulder 1^a and by pressure communicated to the tripping toe of the mating knuckle, the said 80 mating knuckle is at the same time released.

By placing the tripping lever perpendicularly as shown, I am enabled to use a lever of greater length than by placing said lever 85 horizontally, because the car structure limits the length of a horizontal lever, whereas the perpendicular lever may extend a considerable length downward without interference with any part of the car or coupler 90 structure.

In the type of coupler shown and with which the releasing lever described is intended to be used is a carrier block or shoe 95 depending from the under side of the coupler. This carrier block or shoe 14, which supports the train pipe couplings is of great strength and by reason of the presence of this coupling the lever 7 may be extended downward as far as the lower end of the 100 shoe, if desired, the heavy shoe serving to protect the lever from contact with objects in front of the moving car.

The coupler heads described when interlocked form a rigid mass insuring the proper 105 sealing of the joints between the press-on coupling devices 15, 16 and 17, when two cars are coupled. Said press-on couplings are mounted yieldably in a carrier block or shoe 14 by means of flanges 19, engaged by 110 guides 10 cast integral with a coupler head and the rear of the block 14 abuts against a stop lug 13, as more particularly described in a copending application filed by me.

Having described my invention in such 115 manner as to enable those skilled in the art to which it appertains to make and use the same, what I claim and desire to secure by Letters Patent is:

1. The combination of a pair of coupler 120 heads having front abutting faces, a draw bar pivoted within each coupling head, said draw bar having a partly cylindrical front end, each coupler head having a rigid coupling hook adapted to engage with the 125 knuckle of a standard coupler, said hook having a vertical front face oblique to the center line of the coupler heads, the outer side of said hook engaging the side wall of the cavity and the oblique end engaging the 130

partly cylindrical end of the draw bar in a companion coupler when said coupling heads are interlocked, and means for interlocking the said coupler heads.

- 5 2. The combination of a pair of coupler heads adapted to be interlocked, a knuckle, having means to interlock with a companion head, pivoted at one side of each coupler head, each coupler head having a side opening for engagement with the knuckle of a companion head, a hook formed body oppo-

site the engaging portion of each knuckle, and a locking toe opposite the hook formed body of a companion knuckle when in interlocking relation, said hook formed members and locking toes each having a hollow and a swell, the hollows and swells on the hook formed portions interfitting with the swell, and hollows on the locking toes to resist force tending to unlock said knuckles. 15 20

In testimony whereof I affix my signature.
JOHN H. FUNK.
